[57] CLAIM

The ornamental design for a disinfecter unit for cleaning and disinfecting a medical fiberscope, as shown.

DESCRIPTION

FIG. 1 is a perspective view of a disinfecter unit for cleaning and disinfecting a medical fiberscope showing our new design;

FIG. 2 is a side elevational view thereof;

FIG. 3 is a front elevational view thereof; and

FIG. 4 is a perspective view thereof, with the tray lid removed and in storage position on the side of the unit.

FIG. 2.

FIG. 3.

FIG. 4.
